UNITED STATES PATENT OFFICE.

ADELBERT AMES, JR., OF TEWKSBURY, MASSACHUSETTS.

EXHIBITING DEVICE.

1,427,428.

Specification of Letters Patent. Patented Aug. 29, 1922.

Application filed October 3, 1919. Serial No. 328,086.

To all whom it may concern:

Be it known that I, ADELBERT AMES, Jr., citizen of the United States, and resident of Tewksbury, in the county of Middlesex and State of Massachusetts, have invented new and useful Improvements in Exhibiting Devices, of which the following is a specification.

This invention relates to exhibiting devices and more particularly to an exhibiting device for use as a window display or in connection with signs, billboards or the like. In such devices it is highly desirable to secure the appearance of motion or of illumination to attract the attention of the passer-by. With large devices, however, the provision of moving parts is not feasible because of the expense and complexity of power mechanism for operating the movable members and artificial illumination is a source of large cost and upkeep.

The principal objects of the present invention are to obviate the difficulties above enumerated and to provide an exhibiting device which produces the effect of motion but has no movable parts to get out of order, which gives the effect of illumination but requires no artificial illuminants and which is simple in construction.

I will now describe my invention in connection with one specific embodiment of the genus of my invention. In the accompanying drawings:

Fig. 1 illustrates an exhibiting device having a figured surface representing a human face and provided with fixed illusion producing members constructed in accordance with my invention;

Fig. 2 is a transverse section taken on line 2—2 of Fig. 1; and

Fig. 3 is a perspective view of a curved member which simulates an eyelid.

Referring particularly to Fig. 1 of the drawing, I have illustrated a figured surface 1 representing a human face. This surface may be depicted upon any suitable rigid backing such as sheet metal or wooden boarding 2 customarily employed in the construction of signs, billboards or the like. Openings 3 are provided through the backing 2 in positions corresponding to the eye sockets, having outlines similar to eye openings. Suitably attached to the rear side of the backing 2 as by brackets 4 directly back of the openings 3 and spaced a substantial distance therefrom, is a member 5 of any

suitable translucent material such as ground glass. Secured to the front surface of this member and disposed directly back of the center of the openings 3 are members 6 suitably formed and painted to represent eye-pupils. These members may be secured to the member 5 in any suitable manner as by bolts 7. Instead of attaching separate pupil members 6 to the translucent member 5 the pupils may be painted or otherwise depicted directly upon the member 6.

Secured by screws or bolts 8 to the figured side of the backing 2 adjacent the end of an eye opening 3 so as to project outwardly 70 is a curved member 9 (shown in detail in Fig. 3) of sheet metal or other suitable material the surface of which is painted or otherwise formed to represent an eye-lid.

In practice my improved exhibiting device 75 is adapted to be disposed in such position as to be readily observed by persons passing on foot or in vehicles, as for example adjacent to heavily traveled highways or the rights of way of railroads or railways. As the observer approaches the device from one side thereof, the eye-pupils because of the spaced relation between the figured surface and said eye-pupils, will appear to be turned into the corners of the eye openings nearest the 85 observer. As the observer further approaches to a position directly in front of the device the pupils appear to follow his movements and from the latter position appear to be directly in the center of the eye 90 openings. Further movement of the observer past the device brings the observer into a position in which the pupils appear to have moved into the opposite corners of the eye 95 openings or to have turned toward the observer. Thus during the movement of the observer past the device, the observer is given a very realistic impression that the eyes of the figure have followed him.

This illusion of apparent movement may 100 also be produced with respect to one or both of the eyelids of the figure through members such as 9 hereinbefore described. For example, assuming that an observer is passing the device from left to right as viewed in Fig. 1, 105 when he first approaches the device, the lid member 9 does not appear between the observer and the eye opening 3 but blends with the surface of the figure, and the eyes of the figure appear to be wide open. As the observer moves past the device the lid member 9 cuts off an increasing amount of the ob-

server's view of the right hand eye opening until, when he has passed to the right of the device the member 9 cuts off his view of the eye opening entirely. The member 9 thus 5 appears to close the eye in simulation of winking.

A similar member 9 could, within the contemplation of this invention, be applied to the other eye opening. When thus applied 10 with its pointed end 10 toward the left, the illusion of closing both eyes at the same time would be effected, whereas if the members 9 were so positioned as to have their points 10 both turned toward the bridge of the nose, 15 an illusion of opening the left eye and closing the right eye would be produced for an observer passing the device from left to right.

The effect of illumination is secured by the 20 use of translucent material behind the sign opening. This permits natural light to pass through the opening and if the device be so mounted as to permit light to pass through when the roadway is most frequented startling effects are possible through the openings. In the device illustrated the effect is 25 heightened by the opaque pupils which obstruct part of the light. Furthermore, the fact that the device is not at all times illuminated increases its effectiveness on account 30 of its variable appearance.

While I have illustrated my invention specifically in connection with a figure representing a human face it is to be understood 35 as generic in its character and applicable to the production of apparent motion between fixed members of any desired configuration.

I claim:—

1. An exhibiting device comprising an 40 opaque pictorial surface having an opening therein for the transmission of light therethrough, and a fixed opaque element, constituting an apparent continuation of said pictorial surface and having a superficial 45 area less than that of the opening arranged behind and spaced substantially from the plane of said surface to co-act with said opening whereby to obstruct the passage of a portion of the light normally transmitted 50 therethrough.

2. An exhibiting device comprising an opaque pictorial surface having an opening of relatively small area therein, and an opaque member constituting an apparent 55 element of said pictorial surface, said member being of a width less than that of the opening and being fixedly supported in spaced relation to the said surface and at a substantial distance to the rear thereof 60 whereby to obstruct a portion of the light transmitted through said opening.

3. An exhibiting device comprising an opaque, pictorial surface having an opening therethrough, a translucent member fixedly 65 disposed to lie in a plane behind and sub-

stantially spaced from said surface, and a fixedly supported opaque element constructed and arranged to constitute an apparent continuation of said pictorial surface, said element being interposed between the plane 70 of said opening and said translucent member.

4. An exhibiting device comprising a pictorial surface having an opening therein, a translucent member fixedly disposed in a 75 plane to the rear of said surface, and substantially spaced therefrom, and an opaque element fixedly secured to said translucent member, said opaque element constituting an apparent continuation of said pictorial 80 surface, and being of a superficial area less than that of the opening.

5. An exhibiting device comprising a surface having thereon the pictorial representation of a face and provided with openings at 85 the location of the eyes, and fixed, opaque elements formed to represent the eyes of said face and disposed behind the respective openings and in plane substantially spaced from that of the openings whereby to simulate movement of said elements with respect to said face upon relative movement between the device and an observer.

6. An exhibiting device comprising a surface having thereon a pictorial representation of a face and having eye openings therein, and a fixed translucent member disposed in a plane substantially to the rear of said surface having fixed thereon opaque representations of eye-pupils, the said pupils 95 being so disposed upon said member as to appear in alinement with the center of said openings when observed from a point directly in front of said face and to appear 100 to move toward the corners of said eye openings upon relative movement of said device and observer to either side of the central position.

7. An exhibiting device comprising a surface having thereon a pictorial representation of a human face and having eye openings therein, means secured to the rear of said surface having thereon representations of eye pupils, and a member secured in front of one of said openings and formed to simulate an eyelid, said means and member being so disposed relatively to said eye openings 110 as to appear to move with respect thereto upon relative movement between said observer and said device.

8. An exhibiting device comprising a surface having thereon a pictorial representation of a human face, and a member outstanding from said surface in the region of one of the eyes of said face and formed 115 to simulate an eye-lid, the said member being so disposed as to appear to cover the eye upon relative movement between the device and an observer.

9. An exhibiting device comprising a sur- 120

- face having thereon a pictorial representation of a human face and a curved member outstanding from said surface in the region of one of the eyes of said face and formed 5 to represent an eye-lid, the said member being so disposed as to simulate movement of the eye-lid with respect to the eye upon relative movement between the device and an observer.
10. 10. An exhibiting device comprising a pictorial surface having an opening therein and a relatively opaque member constituting
- an important feature of the design of said surface and an apparent continuation of the latter, said member being fixedly disposed 15 substantially in alinement with said opening but in a plane substantially spaced from the plane of said surface said member being smaller than said opening so that a portion only of the light transmitted through said 20 opening is obstructed.

Signed by me at Hanover, New Hampshire, this 24th day of September, 1919.

ADELBERT AMES, JR.
